THERMOELECTRIC GENERATING DEVICE

Eugene Paille, Los Angeles, Calif., assignor to
General Controls Co., Glendale, Calif., a corporation of California

Application February 28, 1944, Serial No. 524,157

7 Claims. (Cl. 136—4)

1

My present invention relates to thermoelectric generating devices and more particularly to those of the type adapted to be heated by electricity.

In control systems energized by alternating current supplied by the service lines, it is sometimes desirable to provide a source of direct current for the operation of a sensitive device such as an electromagnetic relay or pilot valve. For this purpose it has been proposed to employ a thermoelectric generating device, or thermocouple, and to heat the hot junction thereof by means of an electric resistance coil. In spite of the fact that the efficiency of translation of alternating to direct current in such a device is very low, when only a small amount of direct current is required a thermoelectric generator is preferred to a conventional electrical rectifier because of the "smoothness," or absence of periodic interruptions, of the current produced by the former.

It is therefore a main object of this invention to improve the efficiency of electrically-heated thermoelectric generating devices, and I accomplish this object by so arranging the electric heating element with respect to the hot junction of the device that the heating losses of the element, particularly those due to radiation and convection, are reduced to a minimum.

Other objects and advantages of the invention will be found in the description, the drawing, and the claims; and, for full understanding of the invention, reference may be had to the following detailed description and accompanying drawing, wherein:

Figure 1 is a longitudinal sectional view of a thermoelectric generating device embodying the invention; and

Figure 2 is an end elevation of the device shown in Figure 1.

The thermoelectric generating device, as shown in the drawing, comprises a pair of tubular members 11 and 12 intimately joined together at one of their respective ends by a weld 13. The members 11—12 are of thermoelectrically dissimilar materials, such as, for example, the well-known alloys "Chromel" and "Copel," and the welded junction of the members constitutes the "hot" junction of the device.

Fused or welded to the members 11—12 adjacent the free ends thereof are conductors 14 and 15, respectively; the material of each conductor being the same as, or thermoelectrically similar to, the material of the member to which it is attached. In the process of fusing the conductors to the members, the conductor is pref-

erably first so softened by the heat that the member is firmly embedded therein, as is shown in Figure 2. To the free ends of the members 14—15 are welded copper leads 16 for connecting the device to a load 17 which may be, for example, the coil of an electromagnetic relay. The junctions 21 and 22 of the copper leads 16 and the conductors 14—15 constitute effectively the "cold junction" of the device.

If the arrangement is such that the distance between the generating device and the load is short, the copper leads may be dispensed with and the conductors 14—15 connected directly to the load. However, it is not usually advisable to extend the conductors 14—15 to a considerable distance on account of the high electrical resistivity of most materials having good thermoelectric properties.

Within the hollow of the tubular members 11—12, and adjacent the "hot" junction thereof, is an electric heating element 18 which is conveniently in the form of a resistance coil having conducting leads 19 which extend through the outer ends of the members for connection to a source of electricity (not shown), such as that provided by the usual alternating current service. Closing the outer ends of the members 11—12 is a pair of sleeves 20 of heat-insulating material such as porcelain; the sleeves extending in close proximity to the element 18 so as to confine the heat thereof to the hot junction of the device, and having central passages or bores for the conducting leads 19.

In a practical embodiment of the invention, the members 11—12 and conductors 14—15 were constructed of No. 14 gauge "Chromel" and "Copel" wire. The copper leads 16 were also of wire of the same size and hence sufficiently rigid that the device as a whole needed no support other than that afforded by the attachment of the leads to the terminals of the load device or relay. When the amount of energy expended in the heating coil 18 was 5 watts, the amount of energy delivered to load 17 (having a resistance substantially equal to that of the device) was 0.0225 watt; such energy being sufficient to operate a sensitive D. C. electromagnetic relay.

The embodiment of my invention herein shown and described is obviously susceptible of modification without departure from the spirit of the invention, and I intend therefore to be limited only by the scope of the appended claims.

I claim as my invention:

1. A thermoelectric generating device comprising a pair of elongated members of thermoelec-

trically dissimilar materials joined together at one of their respective ends to form a hot junction, said members being hollow at said ends and defining a cavity within said hot junction, and an electric element in said cavity for heating said hot junction, the other of the ends of said members being so remote from said heating element that they are not substantially affected by the heat thereof.

2. A tubular thermoelectric generating device formed by a pair of tubular members of thermoelectrically dissimilar materials joined together at one of their respective ends to form a hot junction, and an electric heating element within said device adjacent said hot junction, the other of the ends of said members being so remote from said heating element that they are not substantially affected by the heat thereof.

3. A tubular thermoelectric generating device formed by a pair of tubular members of thermoelectrically dissimilar materials joined together longitudinally at one of their respective ends to form a hot junction, and an electric heating element within said device adjacent said hot junction, the other of the ends of said members being so remote from said heating element that they are not substantially affected by the heat thereof.

4. A tubular thermoelectric generating device formed by a pair of tubular members of thermoelectrically dissimilar materials joined together at one of their respective ends to form a hot junction, an electric heating element within said device adjacent said hot junction, and insulating means for confining to said hot junction the heat produced by said element.

5. A tubular thermoelectric generating device formed by a pair of tubular members of thermoelectrically dissimilar materials joined together longitudinally at one of their respective ends to

form a hot junction, an electric heating element within said device at and on either side of said hot junction, and heat-insulating material substantially closing the hollow of said device at opposite sides of said hot junction and extending in close proximity thereto.

6. A tubular thermoelectric generating device formed by a pair of tubular members of thermoelectrically dissimilar materials joined together longitudinally at one of their respective ends to form a hot junction, an electric heating element within said device at and on closely adjacent sides of said hot junction and having conducting leads extending through the hollow of the device, and a pair of heat-insulating members substantially closing the opposite ends of said device, said heat-insulating members extending in close proximity to the opposite ends of said heating element and at least one of them providing a passage for a conducting lead of the heating element.

7. A thermoelectric generating device comprising a pair of relatively short tubular members of thermoelectrically dissimilar materials joined together to form a tube providing a hot junction between the members, an electric heating element within said tube at and on closely adjacent sides of said hot junction and having conducting leads extending through the tube, a pair of heat-insulating members substantially closing the opposite ends of the tube and extending adjacent said heating element, at least one of said heat-insulating members providing a passage for a conducting lead of the heating element, and a conductor branching laterally from each of said tubular members adjacent the free end thereof, the material of each conductor being thermoelectrically similar to that of the tubular member from which it branches.

EUGENE PAILLE.
